Des. 224,094
Patented July 4, 1972

224,094

MULTIPLE DWELLING STRUCTURE

Hue R. Lee, 1353 W. Nancy Creek Drive NE.,
Atlanta, Ga. 30319

Filed Oct. 14, 1970, Ser. No. 25,480

Term of patent 14 years

Int. Cl. D25—03

U.S. Cl. D13—1

FIG. 1 is a front perspective view of a multiple dwelling structure with both sides being identical;

FIG. 2 is a front elevation thereof; and

FIG. 3 is a rear view thereof.

I claim:

The ornamental design for a multiple dwelling structure, as shown and described.
